UNITED STATES PATENT OFFICE

2,071,544

SELF-LOCKING SLIDER FOR MULTIPLE FASTENERS

Harry David Kroll, Los Angeles, Calif.

Application December 31, 1934, Serial No. 759,921

6 Claims. (Cl. 24—205)

This invention relates to an improved self-locking slider for multiple fasteners, and the present application shows an improvement over this same inventor's prior application for patent on "locking means for multiple fastener sliders", filed July 27, 1934, Serial No. 737,254, now Patent No. 2,055,903, granted Sept. 29, 1936.

One of the important objects of this invention is to provide an automatic self-locking slider for use with multiple fasteners and which eliminates in a satisfactory manner the usual pull-tab.

Another important object of the invention is the provision in a self-locking slider for multiple fasteners or the like of a key-operated locking means which is independent of the self-locking element and which, like the self-locking element, can be formed to operate on either one or both sides of the fasteners or the line of juncture between the cooperating elements.

Another and further important object of the invention is the provision of a more compact slider element for a multiple fastener construction which shall include a locking means either automatic or key-operated or both and which shall also include a manually-operated element for withdrawing the self-locking latch, which manually-operated element can be fastened in locked position by means of a key.

Other and further important objects of the invention will be apparent from the disclosures in the accompanying drawings and following specification.

The invention, in a preferred form, is illustrated in the drawings and hereinafter more fully described.

In the drawings:

Figure 1 is a top plan view of the improved self-locking slider of this invention, showing the same as applied to the usual multiple fastener construction.

Figure 2 is a view somewhat similar to Figure 1, showing additionally a key-operated structure which can be used either as a separate locking element or as a locking means for the device shown in Figure 1.

Figure 3 is a sectional view taken on the line 3—3 of Figure 1, looking in the direction indicated by the arrows.

Figure 4 is a sectional view on the line 4—4 of Figure 2, looking in the direction indicated.

Figure 5 is a sectional view taken on the line 5—5 of Figure 2, looking in the direction indicated.

Figure 6 is a top plan view of the device shown in Figure 2 with the cover removed.

Figure 7 is an exploded view, showing the key-operated locking structure.

Figure 8 is an exploded view, showing the manually operated or self-locking structure.

Figure 9 is a top plan view of the structure of Figure 7, showing the same assembled and in locking position.

Figure 10 is a top plan view of the structure of Figure 8, parts being broken away and showing the same in released position.

As shown in the drawings:

The reference numeral 10 indicates generally the casing of the improved locking slider of this invention and shows the same as applied to a set of multiple fasteners 12—14 which are fixed to 15 opposed edges of cloth or other material 16—18 adapted to be joined together by the fasteners.

A manually operated latching release element 20 is pivotally mounted in the casing 10 for operation by the thumb of the user, and in Figure 2, the casing 10a is shown with a key-hole 22 adapted for the insertion of a key which operates a further locking or latching element.

As best shown in Figures 3 and 6, the manually-operated latching element comprises essentially a metal plate 24 having an inwardly turned end 26 which is adapted to penetrate between any two of the fastener elements 14, thereby preventing the housing 10 with its appurtenances from motion relatively to the fastener elements 12—14. A leaf-spring 28 normally impels the element 24 with its locking pin 26 into locking relationship with the fastener elements 12—14.

The locking structure 24 and the spring 28 are fastened about a pin 30 which passes through the casing 10, and this pin also furnishes a pivotal mounting for the manually-operated release element 20. This manually-operated element comprises a sort of box-like structure open at its inner face and normally impelled outwardly by means of a coiled spring 32 positioned about the pin 30.

One inner face of the release element 20 is cam-shaped as best shown at 34 in Figure 5 so that inward motion of the element 20 moves the locking plate 24 with its pin 26 upwardly out of locking relationship with the elements 14.

Also positioned in the casing 10a is a key-operated locking structure which comprises essentially a latching element 36 having a projection 38 adapted to enter between any two of the fasteners, and this device is normally impelled into upward non-latching position by means of a leaf-spring 40.

Upon the insertion of a key into the key-hole

22, the flange of the key contacts a slot 42 in a slider 44 mounted in the casing 10a as best shown in Figures 4, 6 and 7, and upon turning of the key, this is moved forwardly over a cammed projection 46 on the element 36, whereupon the locking lug 38 is pushed downwardly or outwardly, as the case may be, into locking relationship with the elements 12. The structure 36 is best shaped as shown in Figures 6 and 7 wherein its forward portion is bent into somewhat U-shape, thereby forming a slot or groove in which a downward projection 48 of the element 44 travels, thereby guiding its forward portion, the rear portion being bifurcated as at 50 and similarly guided about a pin 52.

The whole device is extremely compact, while, at the same time, being simple and readily operated and will constitute quite an improvement over the present-day devices, as it may be used in situations hitherto thought impractical, as, for example, for fastening pockets or for ladies' underwear, or in any other situations where the pull-tab would be either inconvenient or absolutely impractical.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A self-locking slider for multiple fasteners, comprising a casing forming part of the slider, a manually-operated release element pivotally mounted in the casing, a locking element in the casing including a projection adapted to penetrate between adjacent fastener elements, a spring for normally impelling the projection into locking relationship, and cam means on the pivoted element cooperating with the projection for moving the projection out of locking position.

2. A locking device for multiple fasteners, including a slider body, a casing forming part of the slider body, a locking projection mounted in the casing adapted to penetrate between adjacent fastener elements, and key-operated means slideable in the casing for moving the projection into

such locking relationship, said key-operated means including a spring-pressed cam element.

3. A locking device for multiple fasteners, including a slider, a casing forming part of the slider, a locking element mounted in the casing and having a projection adapted to penetrate between adjacent fastener elements, a cam on the locking element and key-operated spring means co-acting with the cam for moving the projection into such locking relationship.

4. A locking device for multiple fasteners, including a slider, a casing forming part of the slider, a locking projection mounted in the casing adapted to penetrate between adjacent fastener elements, and key-operated means for moving the projection into and out of such locking relationship, said key-operated means including a slide having a notch therein for engagement with a corresponding portion of the key, and a support integral with the locking projection, said support being adjacent the slide, and a cam on the support in operative relationship with the slide.

5. A locking device for multiple fasteners, including a slider, a casing forming part of the slider, a locking projection mounted in the casing adapted to penetrate between adjacent fastener elements, and key-operated means for moving the projection into and out of such locking relationship, said key-operated means including a slide having a notch therein for engagement with a corresponding portion of the key, and a support integral with the locking projection, said support being adjacent the slide, and a cam on the support in operative relationship with the slide, together with spring means for normally impelling the projection and its support into non-locking position.

6. A duplex self-locking slider for multiple fasteners, including a slider body, a casing forming part of the slider body, a manually released locking projection in one side of the casing, and a key-operated locking element mounted in the other side of the casing, together with common spring means for the projection and locking element.
